UNITED STATES PATENT OFFICE.

GEORGE WARREN CAMP, OF MOUNT VERNON, NEW YORK, ASSIGNOR TO WARD
LEONARD ELECTRIC COMPANY, A CORPORATION OF NEW YORK.

RHEOSTAT.

Application filed January 10, 1921. Serial No. 436,024.

To all whom it may concern:

Be it known that I, GEORGE W. CAMP, a citizen of the United States, residing at Mount Vernon, in the county of Westchester and State of New York, have invented 5 certain new and useful Improvements in Rheostats, of which the following is a specification.

This invention relates to rheostats or regulators for controlling and adjusting the resistance in an electric circuit to any desired amount. The invention is particularly applicable to that general type of rheostats known as theatre dimmers, and to other uses 15 where it is desired to independently control a number of different circuits.

It has been customary to employ a separate rheostat for each circuit controlled, the rheostat being in the form of a plate with 20 an adjustable arm, and to support a number of these rheostats side by side on a frame with an independent handle for controlling each rheostat. Where the number of circuits to be controlled is comparatively 25 large, this arrangement occupies considerable space, requiring one or more rheostats for each circuit. The space usually provided for this equipment is restricted and in any 30 event, it is desirable to reduce the space required to as small an amount as possible.

The main object of my invention is to economize the space occupied in the above type of rheostats and by means of my invention I can separately control two circuits by a combined rheostatic plate unit 35 occupying the space formerly occupied by one rheostatic plate controlling one circuit. Another object is to produce such a combined unit by a simple form of construction 40 which may be conveniently assembled and manufactured. These and other objects and advantages will be understood from the following description and accompanying drawings, which illustrate one embodiment there- 45 of.

Fig. 1 is an elevation of one side of the combined unit. Fig. 2 is an elevation of the reverse side of the combined unit. Fig. 3 is a sectional view of a portion of the two 50 plates showing the method of securing one within the other. Fig. 4 is a detail showing part of the lever operating mechanism, and Fig. 5 is an edge view of the plate and operating levers.

The rheostat illustrated forms a combined 55 unit comprising two concentric circular rheostat plates, one located within the other. The outer portion of the combined unit includes the metal plate 1 having an upturned outer edge 1^a and an upturned inner edge 1^b. Near the inner edge is a series of circularly arranged fixed contacts 2 extending around the plate; and successively connected between them is the resistance conductors 3. The resistance conductors extend outwardly from the fixed contacts toward the outside rim of the plate as shown in Fig. 1. The resistance conductors and contacts are insulated from the metal plate by an intervening layer of insulating material; and the base portion of the contacts and the resistance conductors are insulated and protected by a coating of insulating material, preferably an adhesive vitreous 70 enamel.

The inner plate in this instance includes an inner plate 4 having an outer upturned edge 4^a. On this plate are two rows of circularly arranged fixed contacts 5. From the outer row the resistance conductors 6 extend outwardly and from the inner row resistance conductors 6^a extend inwardly. These contacts and resistance conductors are 80 fixed in position and insulated from the metal plate and are coated with an insulating protective enamel, the same as the contacts and resistance conductors on the reverse side of the outer plate.

The inner plate is secured within the outer plate by bolts, nuts and washers 7, 90 which pass through cut-away portions in the adjacent rims of the two plates as shown in Fig. 3. Each of the two plates have circular heat radiating rims or flanges 8 on the reverse side from that carrying the fixed 95 contacts.

The inner plate has a central hub through which extends the shaft 9 which is fixed thereto. This fixed shaft carries thereon a rotatable sleeve 10 having integral therewith a disk 10^a. On the inner side of this disk and fixed thereto is the contact arm 11. The inner face of the contact arm carries a conducting strip 11^a, the outer end of which has a contact engagement with the fixed contacts 2, and the inner end of which has a contact engagement with a conducting ring 12 fixed to the inner plate 4, but insulated 100 105

therefrom. Fixed to the rim 1^a, but insulated therefrom, are the four terminals 13. From one terminal 13 a conductor 13^d extends to and is electrically connected with 5 the conducting ring 12. Another terminal 13 is electrically connected by a conductor 13^b to the first fixed contact 2. Evidently movement of the contact arm in a counter-clockwise direction from the position shown 10 in Fig. 1, will gradually increase the amount of the resistance conductors 3 in a circuit connected to the two right-hand terminals 13 of Fig. 1. The contact arm is movable nearly 360°, the stop 14 limiting the movement 15 in the resistance-all-out position and in the resistance-all-in position.

The contact arm is rotated in either direction as desired by means of the hand lever 15, the lower end of which is pivotally 20 mounted on a suitable support. A rod 16 is pivotally connected to the handle 15 and has secured to its inner end the bow or bracket 17. A chain 18 is secured at its ends to the projecting portions of the bracket 17, the 25 chain having a turn around the sleeve 10, one of the links of the chain having a projecting pin 18^b engaging a hole in the sleeve 10, as shown in Fig. 4. Evidently movement of the bow or bracket 17 in either direction by movement of the handle 15, will cause the sleeve 10 and the contact arm 11 to be correspondingly moved in either direction as desired.

On the reverse side of the unit is the contact mechanism for adjusting the resistance of the inner plate. In this instance a conductor 13^c extends from one terminal 13 through an opening in the inner plate and is connected to the first contact of the outer 35 row 5, at the left of the stop 14. Another conductor 13^a extends from the remaining terminal 13 to an insulated terminal 19 which extends through the inner plate. At the opposite side of the plate a conductor 13^e 40 is connected to the terminal 19 and to the first contact of the inner row of fixed contacts 5, at the right of terminal 19 as viewed in Fig. 2.

On the side of the combined unit shown in 50 Fig. 2, the shaft 9 carries another sleeve 20, which is rotatable on the shaft 9 and has an integral flange or disk 20^a. A contact arm 21 is fixed to the inner face of the flange 20^a. One end of the contact arm extends to 55 and has contact engagement with the outer row of fixed contacts 5, while the opposite end of the contact arm extends to and has contact engagement with the inner row of contacts 5. It is evident that in the position 60 shown in Fig. 2, the contact arm makes a direct connection between the contacts to which the conductors 13^c and 13^e are connected, and consequently no resistance is included in the circuit. Rotation of the contact arm in a clockwise direction gradually 65

inserts resistance until the maximum resistance is included by a movement of nearly 360° to the resistance-all-in-position.

The contact arm is operated in the same manner as already described with reference 70 to the contact arm on the other side of the plate, there being a pivoted hand lever 15^a having pivotally connected thereto the rod 16^a to which is also connected a bracket or bow 17^a. The bow 17^a carries the chain 18^a 75 which latter engages the sleeve 20, in the same manner as described with reference to the chain 18 engaging the sleeve 10.

The two plates are evidently readily detachable, one from the other, and easily assembled. In the process of manufacture, the insulating coatings can best be applied with the plates horizontal and the side on which the conductors are located, or to be located, uppermost. With my improved invention 80 in this process, the plates may have the insulating coatings and resistance conductors and fixed contacts applied with the plates detached, or they may be united by the attaching means shown with resistance carrying sides uppermost. After enameling they 85 may be detached and one plate reversed with reference to the other and reassembled, after which the movable parts are added and the auxiliary connections are made. My invention 90 thus gives a convenient method of manufacture and assembly.

It is evident that by my invention the space occupied by the combined rheostatic plate, is no more than that previously occupied by one rheostatic plate and that independent control of two circuits is obtainable. Also by placing the operating mechanism on opposite sides of the unit, the handles are 100 suitably spaced from each other and the amount of axial space required for the two operating mechanisms is also a minimum, and no greater than that required for the 105 suitable and necessary spacing of the operating handles. Additional units may be 110 added for the control of additional circuits and supported on the four parallel bars 22 by means of bolts 23, which engage the slotted ears 1^b formed on the rim of the plate 2; or the units may be otherwise suitably 115 supported in groups up to the number required for any particular installation.

My invention is capable of embodiment in various modifications other than the particular form shown, without departing from the 120 scope thereof.

I claim:—

1. A rheostat comprising a plate, resistance conductors and fixed contacts on one side of said plate, resistance conductors and fixed contacts on the reverse side of said plate within the other set of resistance conductors and fixed contacts, heat radiating flanges on both sides of said plate and located opposite said resistance conductors 125 respectively.

tively, and controlling means on each side of said plate.

2. A rheostat comprising a plate, resistance conductors and fixed contacts on one side of said plate, resistance conductors and fixed contacts on the reverse side of said plate within the other set of resistance conductors and fixed contacts, heat radiating flanges on both sides of said plate, and located opposite said resistance conductors respectively, and controlling means on each side of said plate, said controlling means being independently separable.

3. A rheostat comprising a plate having a central portion and an outer portion, one within the other, resistance conductors and fixed contacts on one of said portions, resistance conductors and fixed contacts on the other of said portions, and controlling means for each of said portions.

4. A rheostat comprising a plate having an inner central portion and an outer portion, resistance conductors and fixed contacts on one side of one of said portions, resistance conductors and fixed contacts on the opposite side of the other of said portions, and controlling means on opposite sides of said plate for each of said portions.

5. A rheostat comprising a plate having a central portion and an outer portion, said portions being detachable one from the other, resistance conductors and fixed contacts on each of said portions respectively, and controlling means for each of said portions.

6. A rheostat comprising a plate having

a central portion and an outer portion, said portions being detachable one from the other, resistance conductors and fixed contacts on one of said portions, resistance conductors and fixed contacts on the other of said portions on the opposite side thereof, and controlling means for each of said portions on the opposite sides of said plate.

7. A rheostat comprising a plate having a central portion and an outer portion located in the same plane, resistance conductors and fixed contacts on each of said portions respectively, and independently operable controlling means for each of said portions.

8. A rheostat comprising a plate having a central portion and an outer portion located in the same plane, resistance conductors and fixed contacts on one of said portions on one side of said plate, resistance and fixed contacts on the other of said portions on the opposite side of said plate, and controlling means on each side of said plate.

9. A rheostat comprising a plate having a central portion and an outer portion located in the same plane, resistance conductors and fixed contacts on one of said portions on one side of said plate, resistance conductors and fixed contacts on the other of said portions on the opposite side of said plate, and controlling means on each side of said plate, said controlling means being independently operable.

GEORGE WARREN CAMP.
